(57) **CLAIM**

(21) Appl. No.: **29/139,660**

The ornamental design for a double layer shade with fabric
roman shade, as shown and described.

(22) Filed: **Apr. 4, 2001**

DESCRIPTION

(51) LOC (7) Cl. **06-10**

FIG. 1 is a front perspective view of a double layer shade
with roman shade showing my design in a fully lowered,
closed position.

(52) U.S. Cl. **D6/575**

FIG. 2 is a left end view thereof.
